W. G. Flynt, Newark, N. J., assignors to Breeze
Corporations, Inc., Newark, N. J., a corpora-
tion of New Jersey

Application June 12, 1935, Serial No. 26,096

8 Claims. (Cl. 123—169)

This invention relates to spark plugs.

In the past considerable difficulty has been experienced with spark plugs in service by reason of the fact that under high temperatures the 5 plugs are not gas tight. Where leaks occur the efficiency of the spark plug is materially reduced. This is particularly noticeable where the spark plugs are used on aviation engines. The broad object of this invention is to provide a spark 10 plug which will be gas tight and maintain its efficiency for long use under heavy stresses such as are found in aircraft practice.

One cause of the failure of spark plugs is the releasing of pressure between the sealing surfaces 15 of the laminated mica insulation and the metal components that support them, due to relatively large differences in the thermal expansion characteristics of the two materials, which permits the invasion of gases at high temperature and pressure between the laminae and other contacting surfaces, the said invasion carrying with it uncombined carbon in finely divided solid form which by its electrical conductivity reduces the 20 ohmic resistance of the insulation to a point below that established at the sparking gap provided. Therefore, a further object of this invention is to provide a spark plug the essential metallic parts of which will have thermal expansion 25 characteristics comparable to that of the insulation material employed and thus maintain the pressure required for sealing over the entire operating temperature range.

In order to have a gas tight spark plug over the entire temperature range encountered during 35 service, it is necessary to provide a plug which will be gas tight at normal temperatures and will remain so at high temperatures. Therefore, a further object of this invention is to provide a method of assembling a spark plug in order to 40 achieve an efficient result. A further, specific object of the invention is to provide means to apply both an axial and a radial load to the parts in the assembly of the spark plug to effectively seal the parts together. By providing 45 effective sealing between the parts the service life of the spark plug is greatly lengthened.

Overheating of the spark plug causes rapid deterioration and consequent failure. It is essential that the heat which accumulates in the 50 spark plug be readily dissipated to prevent overheating. Therefore, a further object of the invention is to provide a spark plug so constructed as to permit the rapid dissipation of accumulated heat. A specific object of the invention is to 55 provide a construction wherein a single metallic

member is in direct contact with the outer portion of the spark plug to permit direct conduction of heat from the center electrode of the spark plug to the outer casing. A further specific object of the invention is to provide a spark plug in which the cross-sectional area of the center electrode is reduced in the upper portion so as to retard the transmission of heat to the upper part of the spark plug, thereby minimizing the temperature at the point where the contact between the conductor cable and the spark plug terminal is made in order that temperatures damaging to the cable insulation may not be transmitted to that point.

Where radio equipment is used in proximity to an internal combustion engine it is necessary to shield the ignition system by surrounding the system with grounded conductive casings to prevent interference with the radio equipment. This shielding must extend to and include the spark plugs. Therefore, a further object of the invention is to provide a spark plug adapted to receive radio shielding elements.

A further object of the invention is to provide a radio shielding means for a spark plug of the type herein described.

Where radio shielding has been used on spark plugs considerable difficulty has been experienced by reason of the overheating and charring of the insulation surrounding the spark plug lead with resultant deterioration and eventual breakdown. Where metallic covered dielectric caps have been used over the upper part of a spark plug, experience has shown that frequently the insulation of the conductor will become in effect vulcanized to the dielectric of the cap, thereby preventing ready separation of the parts for the purpose of servicing. Therefore, a further specific object of the invention is to provide a radio shielding cap for a spark plug having means to space the spark plug conductor from the dielectric of the cap to prevent the insulation of the conductor adhering to the cap, and also to prevent overheating of the cap and conductor.

In the past considerable difficulty has been experienced by reason of overheating and charring of the insulation of the conductor at the point where the contact means from the spark plug makes contact with the conductor. Therefore a further specific object of the invention is to provide a contact means at an end of the conductor which will insure a good contact and at the same time preclude the possibility of burning the insulation of the conductor.

The invention consists of the construction,

combination and arrangement of parts and the steps of the method, as herein illustrated, described and claimed.

In the accompanying drawings, forming part hereof, is illustrated one form of embodiment of the invention, in which drawings similar reference characters designate corresponding parts, and in which:

Figure 1 is an enlarged vertical section through the spark plug;

Figure 2 is an enlarged vertical section through the sealing bushing and compression hoop before the application thereof to the spark plug;

Figure 3 is a vertical section, partly in elevation, showing the spark plug with the radio shielding cap applied thereto;

Figure 4 is a vertical section, partly in elevation, of the shielding cap; and,

Figure 5 is a bottom plan view, on a smaller scale, of the plug shown in Figure 1.

Referring to the drawings, the outer part of the spark plug comprises a shell 6 provided with external screwthreads 7 for engagement in an appropriate opening in a cylinder head. The lower part of the shell 6 is formed with an inwardly curved base 8 having formed therein a plurality of slots 9 to provide a plurality of sparking points or areas 10. The shell 6 is provided with an internal shelf or shoulder 11 and the upper part of the shell 6 is provided with internal threads 12 to receive a retaining means as hereinafter described. A washer 13 may be disposed adjacent the threads 12 to insure a gas tight seal between the shell 6 and the cylinder head of the engine which receives the spark plug.

Disposed in the shell 6 is a center electrode 14 provided with a tip 15. The electrode 14 is formed of a metal having an exceedingly low or practically negligible co-efficient of expansion and the tip 15 may be formed of metal adapted to withstand corrosion and erosion in service. The electrode 14 and the tip 15 may be made of a single piece of metal having a negligible co-efficient of expansion rather than of two pieces. The electrode 14 may be coated with a material of greater heat emissivity than the metal of the electrode 14, to more readily permit conduction of heat from the electrode 14 to the outer part of the spark plug. The tip 15 is formed with a shoulder 16 to receive the sealing means hereinafter described.

Disposed around the electrode 14 and the upper portion of the tip 15 is a mica insulating tube 17 which may be formed from a single sheet of mica wrapped several times around the electrode 14. Around the lower part of the tube 17 is disposed a stack of mica washers 18 which rest on the shoulder 16 of the tip 15. Centrally of the plug and above the washers 18 is disposed a sealing bushing 19 formed with an integral flange 20 having a tapered face 21 adapted to bear against the internal shoulder 11 of the shell 6. The bushing 19 may be made of copper or other metal suitable for rapid conduction of heat.

Surrounding the bushing 19 is a compression hoop 22 formed of a metal having a negligible co-efficient of expansion similar to the electrode 14. The lower portion of the hoop 22 is formed with a flange 23 overlying the flange 20 of the bushing 19.

Above the bushing 19 and hoop 22 and surrounding the tube 17 is a second stack of mica washers 24. Above the washers 24 and surrounding the upper end of the electrode 14 is a terminal 25 provided with an annular groove 26

to receive a contact means to supply current to the electrode 14. The upper portion of the electrode 14 is formed with a bore 27 which extends to a point adjacent the top of the bushing 19. The purpose of the bore 27 is to reduce the cross-sectional area of the upper portion of the electrode 14 to retard the passage of heat to the upper part of the spark plug. When the spark plug is assembled the top of the electrode 14 is turned over at 28 against the terminal 25 to hold the parts together as hereinafter described. A compressible washer 29 is disposed on the flange 23 of the hoop 22 and the electrode 14 with its associated parts is held in the shell 6 by a retaining cap 30 having a lower threaded portion 31 adapted to engage with the internal threads 12 of the shell 6. The lower part of the retaining cap 30 bears against the washer 29 which serves the purpose of equalizing the pressure at all points on the flange 23. The upper portion of the retaining cap 30 is formed with threads 32 to provide for the optional application to the spark plug of a radio shielding cap as hereinafter described.

In the manufacture of the spark plug the electrode 14 and the tip 15 are first formed. If a two piece construction is used, the tip 15 is welded to the electrode 14 and the parts are machined to exact size to form the shoulder 16. If a one piece construction is desired, the electrode 14 and the tip 15 are machined directly from a single blank. The bore 27 is then formed in the electrode 14 which is now ready to receive its associated elements.

A sheet of mica is then wrapped around the electrode 14 to form the tube 17 and the lower stack of mica washers 18 is applied thereover. The sealing bushing 19 and the compression hoop 22 are next applied and when first applied to the electrode 14 the bushing 19 and the hoop 22 are in the shape shown in Figure 2. The two members may be applied as a sub-assembly or may be applied separately. In either case, before application, the bushing 19 and the hoop 22 are stressed outwardly by means of an expanding drift so that when these members are reduced by swaging as hereinafter described, there will be no tendency on the part of the metal to again expand. The upper stack of mica washers 24 is then applied, followed by the terminal 25. When these parts have been assembled they are placed in an appropriate fixture and an axial load is imposed on the terminal 25 to effectively seal all of the elements surrounding the electrode 14 together. While the parts are maintained under the axial load the upper end of the electrode 14 is turned over at 28, against the terminal 25 to permanently retain the parts in sealed relation. In the assembly thus far the tube 17 has not been distorted.

The bushing 19 and the hoop 22 are then reduced by passing the entire assembly through a swaging die. As shown in Figure 2, the flange 20 of the bushing 19 is provided with a slightly tapered face 21. The face 21 is so tapered to avoid drag on the swaging die which would result if the face 21 were square. The swaging of the members 19 and 22 compresses the tube 17, as shown in Figure 1, and forces the central portion of the bushing 19 closer to the electrode 14. The radial load thus imposed causes an effective sealing of the several parts and causes a slight elongation of the members 19 and 22, which results in an increase in the axial load already imposed on the parts, and incidentally estab-

lishes an initial axial stress approximating the elastic limit of the central electrode material thus maintaining the necessary pressure between the mica laminae and adjacent metallic parts to insure the maintenance of a permanent gas tight seal under all normal operating conditions. This forms a permanent gas tight seal between the several parts, and since the electrode 14 and the hoop 22 are formed of metals having a negligible co-efficient of expansion, there is no possibility of leakage under the high temperatures encountered in service. At the same time, since the bushing 19 and the hoop 22 were initially expanded before being swaged, they are in practically a normal rather than stressed condition after being swaged, so that there is no tendency to expand.

Where a single sheet of mica is used to form the tube 17 there may be very minute interstices left at the ends of the sheet. In a horizontal section these interstices would appear substantially as triangular spaces, the base of the triangle being the thickness of the mica sheet. As a matter of commercial production it is not always feasible to use a single sheet of mica to form the layers of the tube 11. Where several smaller sheets of mica are successively applied to form the tube 17 there is an overlapping of the ends of adjacent sheets of mica. At each point where one sheet of mica overlaps another a minute space will be left in the tube 17, which space will extend the length of the tube 17. In order to prevent the possibility of leakage through these spaces longitudinal of the tube 17, it is advisable to effectively seal the junctions between the several sheets of mica used, or where a single sheet of mica is used, to seal the junctions between the ends of the sheet and the center electrode 14, and the sealing bushing 19, respectively. The sealing may be accomplished by the use of a suitable filler or sealing agent which will fill in minute interstices formed as above described.

The sealing may be accomplished in the following manner: After the tube 17, the bottom washer assembly 18, and the sealing bushing 19 have been applied to the electrode 14, and before the application of pressure as above described, the sealing agent may be incorporated. The sealing agent may be rendered liquid through heating and incorporating by saturation through immersion. The sealing agent may be forced into the interstices under pressure in order to assure complete filling. If an effective seal is achieved over the area adjacent the sealing bushing 19 it is not necessary to apply the filler above the bushing 19. However, if desired, the filler or sealing agent may be applied after the washer assembly 18 and the cap 25 are applied, but before the application of pressure.

When the sealing agent has been incorporated the parts are subjected to the axial load hereinbefore described and also subjected to the radial load. The pressure thus applied will extrude any surplus volume of the sealing agent and effectively eliminate the possibility of leakage through any interstices which may have existed adjacent the ends of the sheets of mica used to form the tube 17.

The electrode 14 with its assembled parts is then machined to form the mica washer stacks 18 and 24 to the contour shown and to present a smooth finish. At the same time the compression hoop 22 is machined from the shape shown in Figure 2 to the shape shown in Figure 1 to

provide the flange 23. The tapered face 21 of the flange 20 on the bushing 19 is also machined to form the face 21 at an angle complementary to the angle of the shoulder 11, so that the two parts will lie flat together. The parts are now ready to be assembled with the shell 6, and when the washer 29 has been applied the electrode 14 and its associated parts are inserted in the shell 6 and held in place in the obvious manner by the retaining cap 30.

When it is desired to apply radio shielding to the spark plug, such shielding may be applied as shown in Figures 3 and 4. A metallic cap 33 is provided and adapted to be placed over the upper end of the spark plug. The cap 33 may be in the form of an elbow as shown, or may have a different shape. The lower edge of the cap 33 is formed with a bead 34 which is adapted to be engaged by a coupling nut 35 formed with a flange 36 which is turned over the bead 34. The nut 35 is free to rotate on the cap 33 and is adapted to engage the threads 32 on the upper part of the retaining member 30 while the lower skirt of the cap 33 contacts the member 30. In this way a good electric contact is made and the cap 33 may be readily removed for the purpose of inspecting or servicing the spark plug.

The cap 33 is provided with a dielectric lining 37 having a thickness sufficient to effectively insulate the terminal 25 and the contact means 30 hereinafter described from the cap 33. The upper portion of the lining 37 is formed with a bore 38 to receive a conductor with its insulation. In order to prevent the insulation of the conductor from being vulcanized to the walls of the bore 38 by reason of the high temperatures encountered, the walls of the bore 38 are formed with ribs 39 which space the insulation of the conductor from the walls and provide a passage for the circulation of air.

Carried by the lining 37 is a threaded bushing 40 in which is threaded a contact screw 41 to the lower end of which is connected a spring 42 adapted to make contact with the terminal 25 of the spark plug. The upper end of the screw 41 is provided with a point 43 adapted to make contact with the conductor.

A conductor 44 surrounded by insulation 45 is provided to supply current to the spark plug. In the past, it has been the practice to extend the insulation 45 to the left hand end of the bore 38 and the point 43 of the screw 41 was used to pierce the insulation 45 to make contact with the conductor 44. This practice causes burning of the insulation 45, which is undesirable. In order to avoid this condition the conductor 44 is extended to the end of the bore 38 but the insulation thereof 45 is removed for an appreciable distance, as shown in Figure 3. A coil spring 46 is connected to the conductor 44 and surrounds the conductor. The contact screw 41 extends partially through the coil spring 46 to make an effective electrical contact by reason of the resilience of the spring 46, and at the same time the danger of burning the insulation 45 is eliminated.

At the point where the conductor 44 with its insulation 45 leaves the cap 33, a conical packing 47 provided with a copper or other metallic re-inforcing means 48 is disposed. The packing 47 may be of the type shown in co-pending application, Serial No. 731,833, filed June 22, 1934, and not only provides a waterproof joint, but the metallic portion 48 serves to improve the electrical contact between the cap 33 and a radio

shielding conduit 49 which surrounds the conductor 44 with its insulation 45. The conduit 49 is provided on its end with a ferrule 58 formed with a flange 51, and a coupling nut 52 serves to hold the conduit 49 against the cap 33 by reason of engagement with threads 53 formed on the cap 33. The pressure of the ferrule 58 against the packing 47 has a tendency to force the packing 47 inwardly against the insulation 45, thereby holding the conductor 44 firmly in place and removing any strain from the end of the conductor, which eliminates the possibility of breakage of the conductor 44 at the point of contact with the screw 41.

15 The general structure of the shielding cap and contact means may be the same as shown in co-pending applications Serial No. 481,766, filed Sept. 13, 1930, and Serial No. 657,166, filed Feb. 17, 1933. The structure of the conduit may 20 be the same as shown in co-pending application Serial No. 657,167, filed Feb. 17, 1933.

Having thus fully described the invention, what is claimed as new and desired to be secured by Letters Patent is:

25 1. A spark plug comprising a shell, an electrode supported in the shell, a tube of insulation disposed around the electrode, a sealing bushing disposed centrally of the electrode and in intimate thermal contact with the insulation, said 30 bushing having formed thereon a flange in contact with the shell, additional insulating material around the electrode above and below the bushing, a compression hoop surrounding the bushing and a retaining means to hold the parts 35 in the shell.

2. A spark plug comprising a shell, an electrode supported in the shell, a tube of insulation disposed around the electrode, a sealing bushing disposed centrally of the electrode and in intimate 40 thermal contact with the insulation, said bushing having formed thereon a flange in contact with the shell, additional insulating material around the electrode above and below the bushing, a compression hoop surrounding the bushing 45 and a retaining means to hold the parts in the shell, said retaining means being formed to receive a radio shielding means.

3. A spark plug comprising a shell, an electrode supported in the shell, a tube of insulation 50 disposed around the electrode, a sealing bushing disposed centrally of the electrode and in intimate thermal contact with the insulation, said bushing having formed thereon a flange in contact with the shell, additional insulating material 55 around the electrode above and below the bushing, a compression hoop surrounding the bushing and a retaining means to hold the parts in the shell, said electrode being formed with a bore to reduce the cross-sectional area of the 60 electrode above the bushing.

4. A spark plug comprising an electrode of metal having a negligible co-efficient of expansion, a body of insulation around the electrode, a sealing bushing around a portion of the insulation, said bushing being formed of metal adapted to readily transmit heat and formed with a flange to dissipate heat directly to the outside of the plug, a compression hoop formed of metal having a negligible co-efficient of expansion

around the bushing, a shell in which the foregoing elements are supported and a retaining means co-operating with the shell to hold the elements in the shell.

5. A spark plug comprising an electrode of metal having a negligible co-efficient of expansion, a body of insulation around the electrode, a sealing bushing around a portion of the insulation, said bushing being formed of metal adapted to readily transmit heat and formed with a flange to dissipate heat directly to the outside of the plug, a compression hoop formed of metal having a negligible co-efficient of expansion around the bushing, a shell in which the foregoing elements are supported and a retaining means co-operating with the shell to hold the elements in the shell, said electrode being formed with a bore to restrain the transmission of heat above the sealing bushing.

6. A spark plug comprising an electrode of metal having a negligible co-efficient of expansion, a body of insulation around the electrode, a sealing bushing around a portion of the insulation, said bushing being formed of metal adapted to readily transmit heat and formed with a flange to dissipate heat directly to the outside of the plug, a compression hoop formed of metal having a negligible co-efficient of expansion around the bushing, said compression hoop being in close thermal contact with both said bushing and the outside member of the plug to permit ready dissipation of heat, a shell in which the foregoing elements are supported and a retaining means co-operating with the shell to hold the elements in the shell.

7. A spark plug comprising an electrode of metal having a negligible co-efficient of expansion, insulation in the form of a tube made from a sheet or sheets of mica wrapped around the electrode, the interstices adjacent the ends of the sheet or sheets being filled with a sealing agent to prevent leakage, a sealing bushing around a portion of the insulation, said bushing being formed of metal adapted to readily transmit heat and formed with a flange to dissipate heat directly to the outside of the plug, a compression hoop formed of metal having a negligible co-efficient of expansion around the bushing, a shell in which the foregoing elements are supported and a retaining means co-operating with the shell to hold the elements in the shell.

8. A spark plug comprising an electrode of metal having a negligible co-efficient of expansion, a coating on the electrode to increase the thermal emissivity of the electrode, a body of insulation around the electrode, a sealing bushing around a portion of the insulation, said bushing being formed of metal adapted to readily transmit heat and formed with a flange to dissipate heat directly to the outside of the plug, a compression hoop formed of metal having a negligible co-efficient of expansion around the bushing, a shell in which the foregoing elements are supported and a retaining means co-operating with the shell to hold the elements in the shell.
